UNITED STATES PATENT OFFICE.

RICHARD RABY, OF LOUDONVILLE, OHIO, ASSIGNOR OF ONE-HALF TO GEORGE F. RABY, OF LOUDONVILLE, OHIO.

SPACING ATTACHMENT FOR T-SQUARES.

1,359,743.

Specification of Letters Patent. Patented Nov. 23, 1920.

Application filed January 20, 1920. Serial No. 352,803.

To all whom it may concern:

Be it known that I, RICHARD RABY, a citizen of the United States, residing at Loudonville, in the county of Ashland and State of Ohio, have invented certain new and useful Improvements in Spacing Attachments for T-Squares, of which the following is a specification, reference being had therein to the accompanying drawing.

10 The invention relates to spacing attachments for T-squares and has for its object to provide an attachment, which attachment is slidably mounted on the T-square blade so that the same may be moved longitudinally and to provide on said slidable attachment a second slidable attachment which may be moved intermittently in parallelism with the T square blade thereby allowing the drawing of lines equally distanced apart.

20 A further object is to provide the intermittently movable member with a paper engaging roller, which roller is provided with graduations adapted to register with an indicator on the intermittently movable member so that equally spaced lines may be drawn when the indicator and scale graduation of the roller are in registration.

30 A further object is to provide an outwardly adjustable member carried by the intermittently movable member whereby after a line has been drawn along the straight edge of the intermittently movable member, and the desired spacing placed in the space between the straight edge and the 35 outwardly adjustable member, the intermittently movable member may be moved so that the outwardly adjustable member will register with the drawn line and the straight edge thereby placed in position for drawing 40 the next line.

45 With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

50 In the drawings:

Figure 1 is a perspective view of the T square attachment showing the same attached to a T square and disposed on a drawing board.

55 Fig. 2 is a sectional view taken on line 2-2 of Fig. 1.

Fig. 3 is a sectional view taken on line 3-3 of Fig. 1.

Fig. 4 is an enlarged plan view of the T square attachment. 60

Fig. 5 is a sectional view taken on line 5-5 of Fig. 4.

Fig. 6 is an enlarged sectional view taken on line 6-6 of Fig. 4.

Referring to the drawings, the numeral 1 designates a conventional form of T square, which T square is provided with a conventional form of T head 2 and a protractor head 3 whereby the blade 4 of the T square may be adjusted at various angles. Disposed 70 on the blade 4 of the T square is a plate 5, which plate is provided with a longitudinal flange 6 overlying one edge of the blade 4. Secured to the plate 5 by means of the screw 7 which passes through an elongated slot 8 is 75 a right angled clip 9, the flange 10 of which overlies the edges of the blade 4 at the opposite side of the flange 6. It will be seen that when the plate 5 is on the blade 4 and the flanges 6 and 10 are in engagement with the 80 edges of said blade that the plate will be held on the blade against wobbling. It will also be seen that the plate may be slid longitudinally on the blade to any position desired. Disposed on top of the plate 5 is a 85 slideable plate 11, which plate is adapted to be slid inwardly and outwardly at right angles to the blade 4 of the T square. Plate 11 is provided with elongated slots 12 at its ends and through which plates guide screws 90 13 pass. Guide screws 13 are placed in right angle alinement to the blade 4 and snugly fit the elongated slots 12 so that as the slideable plate 11 is moved intermittently, the front straight edge 14 will move in parallelism with the edge 15 of the blade 4 so that any lines drawn along the straight edge 14 will be parallel to the straight edge 4. Slideable plate 11 extends forwardly of the edge 15 of the blade 4 and inclines downwardly until its forward end is in the same plane with the under face of the blade 4 so that said forward edge will rest upon the paper during a drawing operation. Plate 11 at a point adjacent the edge 15 of the blade 105 4 is provided with an elongated cut away portion 16 and in alinement with said elongated cutaway portion 16, the plate 11 is bent upwardly so as to form the convex portions 17. The outer ends of the convex portions 17 are provided with downwardly extending ears 18, in bearings of which the

95

100

105

110

pintles of a rubber roller 19 are journaled. By providing the convex portions 17 it will be seen that the upper side of the roller when journaled in the bearings of the ears 5 18 will project for a greater part of its length upwardly through the elongated opening 16 so that the same may be engaged by the fingers of the operator as the slidable member 11 is intermittently moved during a 10 line spacing operation. The forward edge of the opening 16 is provided with an upturned lip 20 so that the operator, during a line spacing operation, will be prevented from engaging the roller with the fingers, at 15 a point which would cause a backward slipping of the slidable plate 11.

Secured to one edge of the forward portions of the slidable member 11 is an adjustable space indicating arm 21 which arm is 20 adapted to be adjusted so that its end 22 may be spaced in relation to the edge 14 according to the width of spacing desired between the lines to be drawn. When it is desired to draw a line spaced from another line the 25 end 22 is adjusted the proper distance in relation to the straight edge 14. Then the operator draws a line along the straight edge, after which he places his fingers in engagement with the roller 19, then rotates 30 the roller so as to move the slidable member 11 in the direction of the arrow α until the end 22 comes into registration with the line which has been drawn at which time the 35 second line is drawn. The above operation being repeated as many times as desired. It will be seen that by the use of the protractor head **T** square that it will be possible to make equally spaced lines at any angle. The 40 roller 19 at one or both of its ends is provided with graduations 23, which graduations may be used for spacing, independently of the adjustable member 21 by bringing any one of its graduations in registration with indicator pointers 24 carried on the 45 convexed portions 17.

From the above it will be seen that a line spacer is provided which is formed from a single sheet of metal and one wherein by the engagement with the paper of the rubber roller during a shifting operation, the 50 possibility of making irregular lines is obviated.

The invention having been set forth what is claimed as new and useful is:

1. A line spacer for **T** squares, said line 55 spacer comprising a plate adapted to be

received by the **T** square blade, a slidable plate slidably mounted and guided at a right angle to the **T** square blade and mounted on the **T** square plate, said slidable plate extending beyond one edge of the blade and having its edge in parallelism with the edge of the blade, a graduated roller carried by said slidable plate and adapted to engage the surface on which the **T** square blade rests, and indicator pointers on the slidable plate 60 adjacent the graduated roller. 65

2. A line spacer for **T** squares, said line spacer comprising a plate carried by the **T** square blade, a plate slidably mounted on the **T** square plate and slidable at an angle 70 to the **T** square blade, said slidable plate extending outwardly from the blade and inclined downwardly, said slidable plate being provided with convexed portions, and an elongated aperture disposed between the 75 convexed portions, a rotatable graduated roller rotatably mounted in bearings of the plate and disposed below the convexed portions and having its upper side protruding through the elongated aperture, said roller being adapted to be engaged by the fingers so that the slidable plate may be intermittently moved during a line spacing and drawing operation, and indicator pointers 80 on the slidable plate adjacent the graduated roller to indicate equal spacing lines. 85

3. A line spacer for **T** squares, said line spacer comprising a plate carried by the **T** square blade, a plate slidably mounted on the **T** square plate and slidable at an angle 90 to the **T** square blade, said slidable plate extending outwardly from the blade and inclined downwardly and provided with convexed portions, and an elongated aperture in the plate disposed between the convexed portions, a rotatable roller rotatably mounted in bearings of the plate and disposed below the convexed portion and having its upper side protruding through the elongated aperture, said roller being adapted to be engaged by the fingers so that the slidable plate may 95 be intermittently moved during a line spacing operation, and an adjustable finger extending beyond the forward edge of the slidable plate and adapted to be moved into registration with each line as it is drawn 100 along the forward edge of the slidable plate. 105

In testimony whereof I hereunto affix my signature.

RICHARD RABY.
